PAINT STRIPING DEVICE

Karl V. Eklov, Detroit, Mich.

Application March 26, 1934, Serial No. 717,453

5 Claims. (Cl. 91—62.6)

My invention relates to a paint striping unit and is a modification and improvement of my former device described in my patent application Serial No. 675,594, filed June 13, 1933.

5 The object of my invention is to produce a striping unit adapted for making fine stripe lines along finished painted surfaces.

Another object is to produce a special paint striping device of simple construction having both 10 the striping unit and paint chamber within a single unit casing, adapted for flowing paint to the striping unit in various positions.

A further object is to produce a striper device of a construction adapted for single or multiple 15 striping units mounted therein, each capable of producing a separate striping line when contacted and displaced by an engaging surface.

A still further object is to produce a striping device with special guard operating units, designed 20 to function to start or cut a line at chosen points.

These several objects are attained in the preferred form by the construction and arrangement of parts more fully hereinafter set forth.

Similar parts on all drawings are marked by 25 similar numerals or letters.

Fig. 1 is an elevation of a single unit striping device showing the exterior arrangement of the operating parts.

Fig. 2 is a top view of the same unit showing the 30 special striper guard mounted on the guide frame.

Fig. 3 is an end view of the striper device as shown in Fig. 2, showing the cylindrical casing member and the guide frame mounted thereon.

Fig. 4 is an end view taken on the line 4—4 of 35 the Fig. 2 showing the relative positions of the striping unit and the guide frame and the general arrangement of the guard unit.

Fig. 5 is a sectional view taken on the line 5—5 of the Fig. 2 showing the general arrangement of 40 the interior operating parts.

Fig. 6 is a cross-sectional view through the casing, taken on the line 6—6 of the Fig. 1 showing the slide means for retaining the adjustable striping unit in position.

45 Fig. 7 is another cross-sectional view through the casing taken on the line 7—7 of the Fig. 1, showing the striping unit nib and the paint passage channel therethrough.

Fig. 8 is a vertical sectional view lengthwise of 50 the casing, taken on the line 5—5 of the Fig. 2 showing the arrangement of a modified form of striper having multiple striping units mounted therein.

Fig. 9 is a cross-sectional view taken on the 55 line 9—9 of the Fig. 8, showing the paint passage

channels provided leading to the respective striping units.

Fig. 10 is another cross-sectional view through the casing taken on the line 10—10 of the Fig. 8, showing the series of slide means formed therein 5 for retaining each of the adjustable striping units in position.

Fig. 11 is a horizontal sectional view through one of the adjustable striper unit bars and its enclosing casing, showing its detail construction and 10 operating means.

Fig. 12 is an elevation of the same unit as shown in the Fig. 8 but with the casing modified by an added paint reserve tank.

Fig. 13 is a cross-sectional view through the casing 15 taken on the line 13—13 of Fig. 12 showing the various paint passages throughout both casing and striping units adjustably mounted therein.

Fig. 14 is another cross-sectional view as taken on the same line 13—13 of the Fig. 12 showing a 20 modified arrangement of paint passages leading directly from the paint container to the respective striping units.

In general, my striping device comprises an elongated hollow casing member having a guide 25 frame fixedly mounted on one end thereof, designed to engage some pre-determined form of guiding template, and adjustable paint striping nibs slidably mounted within the casing member and projected therefrom, through the guide frame 30 section end, at chosen positions, the guide frame being provided with an adjustable guard for the striping units.

I will now describe more fully the detailed 35 construction of my device, referring to the drawings and the marks thereon, describing more specifically the single striping unit type as shown in Figs. 1 to 7 of the drawings, also with the multiple unit type as shown in the Figs. 8 to 14 as a modification thereof.

The casing 1 is made of metal, either cast or turned, and preferably formed in an elongated hollow, tubular body section *a*, open at one end and provided with internal end threads *b* formed therein, the opposite casing end being formed 45 with an internally threaded neck section *c*, and which carries a casing cap 2 threadably mounted therein. The casing cap 2 is preferably formed with a small air vent opening 3 therethrough, opening into the casing chamber *A*, but which 50 may be closed, when desired, by the small cap disc 4 pivotally mounted on the cap top. The open end of the casing 1 is threadably mounted on a head block 5, engaging a threaded collar 6 provided thereon, uniting the two sections as 55

a single solid member. Through the center of the head block 5, inside the casing 1, is mounted an elongated slide block 7, fixedly and rigidly attached thereto, and positioned at right angles to the head block face, concentric with the casing axis, said slide block being extended nearly the entire length of the casing chamber A. Through the center of the slide block 7 is formed a cylindrical slide channel 8, extending the full length thereof, said channel being positioned concentric with the casing axis and formed with a short rectangular slide section d near the inner end thereof, and carries slidably mounted therein a slide rod 9, also formed with a like rectangular slide section e thereon, suitable to engage and fit the channel slide d, yet slide freely therein, the rod slide e being slightly longer than the inclosing casing slide d, allowing a slight endwise adjustment of the rod section therein, while the rectangular sections of the slides d and e are designed to prevent rotation of the rod 9. Any splining means which allow longitudinal adjustment of the slide rod 9 without rotation, may be used in place of the rectangular slide sections shown. The inner end of the slide rod 9 is threaded, and carries an adjustable stop nut 10 threadably mounted thereon. The rod 9 also carries a circular contact washer 13 and a compression coil spring 14 mounted thereon, positioned to engage the shouldered end of the casing slide d, and carries fixedly mounted on the outer end thereof a tubular paint striping nib 11 which also engages the coil spring 14, causing said spring to function when properly stressed, for retaining the assembled striping unit B in its extended closed position as shown in the Fig. 5 of the drawings, the stop nut 10 operating as a stopping means for the striping unit when adjusted to the slide channel ends. The striping nib 11 is preferably made of the type and design as shown and described in my former patent application, Serial No. 484,283, filed Sept. 25, 1930, and is applied herein to illustrate any type of striping nib unit as may be adaptable to this type of striping device. The nib 11 herein shown, comprises a hollow, cylindrical casing f of a diameter for slidably mounting same within the slide channel 8, and is formed with a circular disc recess g at the outer end thereof, and which carries a thin, circular marking disk h rotatably mounted therein, but positioned with the disc edge projected outside the inclosing casing end. The casing channel K being extended from the disc recess g, aximetrically therethrough to the opposite casing end, and receives the end of the slide rod 9 fixedly and securely fitted therein, forming a rigid and continuous striping unit B. When a wide striping disc h is used, it is desirable to mount a paint retaining disc spring 12 within the disc recess g, and which partially encloses the marking disk h, contacting the disc edges, and functions to remove any excess paint from the disc edges as it is rolled along a painted surface, designed to prevent running of newly painted stripe lines. The specific structure of this type of paint striping nib is fully described in patent application last previously mentioned. The hollow nib casing f is provided with a wall port m formed therethrough, opening into the casing chamber K, and is positioned to coincide with the slide channel port p, only the striping unit B is longitudinally displaced within the slide channel 8, by applying pressure to the extended striping disc edge while using the device on a painted surface. Said displacement of the strip-

ing unit B automatically opens the liquid paint passages from the paint container chamber A of the casing 1 directly into the nib chamber K, and when the pressure is released on the striping unit disc h, the compression coil spring 14 will close the paint passages by a return displacement of the striping unit.

The head block 5 may be extended to any required design or formation, for forming a guiding unit for the striping, depending upon the type and structure of template with which it is to be used, and is herein illustrated as being formed with an extended guide rib r along one edge thereof and provided with contact guide groove and slides s and t, designed to engage and fit special template guide slide bars u and v respectively, as indicated by the dotted sections in Fig. 1 of the drawings. However, any type of striping guide members may be used.

Through the head block 5 are formed parallel slide grooves 15 and 16, positioned parallel to the guide contact surfaces s and t, and carry slidably mounted therein a guard slide frame C, formed of parallel slide rods 17 and head bar 18 fixedly attached thereto. Compression coil springs 19 are mounted on the slide rods 17 and engage the edge of the head block 5, designed to displace said guard frame away from the head block when released. Through the center of the head bar 18 is mounted a curved flexible spring bar 20 having its free end positioned near, and at one side of the striping disc edge h, so as to engage and cover the disc edge when the guard frame C is displaced toward the head block 5 by pressure applied thereon against the slide springs 19, thus preventing the striping disc h from operating. This guard unit provides means for cutting and terminating the stripe lines at any chosen point along the template, by providing proper template stops thereon for engaging and displacing the guard unit beneath the striping disc, or to allow a definite starting of the line when operated in the reverse direction, the paint chamber A being previously filled with liquid striping paint by removing the casing end cap 2. The striping is used in the ordinary manner.

A modified form of my striping device is illustrated in Figs. 8 to 14 of the drawings, applying multiple striping units B therein instead of the single striping unit previously shown. The slide block 1a is formed with three parallel slide channels 8a, positioned one above the other as illustrated in Figs. 8, 9 and 10. The structure of each striping unit B is exactly the same as in the former type heretofore described for the single unit, each functioning and operating independently of the other, designed to produce equally spaced multiple stripe lines over a painted surface even though said surface may be slightly irregular. The respective slide channel 60 ports 8a may be formed in the slide block 1a in the same manner as in the former case, each opening separately into the casing paint chamber A by separate passage channels as illustrated in the Fig. 13, or as is shown in the Figs. 8 and 9, comprising a continuous vertical passage channel, open when all striping units B are displaced simultaneously within the supporting slide block. The remaining structure and operation is the same as heretofore described. In all cases, the tubular casing 1 forming the paint chamber A, completely incloses the striping unit slides at all times, and provides a steady flow of paint to the striping nib chamber K for nearly all positions of the striping device.

When the striping device is to be used continuously in one position, an added paint reserve tank 21 may be mounted on the top side of the casing, opening therein as illustrated in Fig. 12 of the drawings. This serves to increase the paint capacity, and to retain the paint chamber A full at all times, insuring a continuous paint flow for all positions of the striping device. The Fig. 14 illustrates a modification of the reserve tank mounting, where the tank neck is extended to open directly into the slide block channel ports p, each striping unit B being provided with a separate channel passage leading thereto. The remaining structure and operation is the same as in the former case.

It is apparent that my device is adapted to various modifications in both structure and detail design, and without departing from the spirit of my invention, and I claim the striping device as herein illustrated and any modification thereof that is substantially a substitution of parts herein shown.

Having fully described my improved paint striping device, what I claim as my invention and desire to secure by Letters Patent is:

1. A paint striping device adapted for making fine stripe lines on smooth surfaces and used with liquid paint, comprising a closed tubular paint container casing having a guide frame unit fixedly mounted on one end thereof, said container casing being provided with a closable filling wall opening, a paint striping unit with striping nib end slidably mounted through said casing wall positioned within the guide unit and projected inside the paint container chamber, spring means mounted within said chamber for engaging said striping unit capable of restraining same to a predetermined position therein, said striping unit being formed with a paint passage therethrough leading to the striping nib end and positioned to open into the paint container chamber for one displaced position of the slidably mounted striping unit within the supporting casing member.
2. A paint striping device adapted for making stripe lines on smooth surfaces and used with liquid striping paint, comprising an elongated, hollow, paint container casing having a guide frame unit fixedly mounted on one end thereof, said paint container casing being provided with a closable wall opening at the opposite end thereof, slide support means mounted within said casing and projected through the guide unit casing end, a paint striping unit with striping nib end slidably mounted within the slide support and having the striping nib end positioned within the guide unit, adjustable therein, said striping unit being formed with a paint passage channel and wall port leading to the striping nib end, and a wall port formed through the supporting slide supports opening into the paint container chamber, positioned to coincide with the striping unit wall port when said striping unit is depressed within the slides, and spring means mounted on said striping unit for restraining it in an extended position outside the guide unit when said unit is disengaged.
3. A striping device adapted for making stripe

lines on smooth surfaces and used with liquid paint, comprising a tubular paint container casing having a guide frame unit fixedly mounted on one end thereof, a slide block fixedly mounted within the casing and extended through the guide unit casing end, said slide block being formed with a slide channel lengthwise therethrough, a striping unit with striping nib end slidably mounted within said slide block channel positioned with the striping nib end within the guide unit, and adjustable therein, spring means mounted on said striping unit within the slide channel for engaging same and displacing the said striping unit to a chosen position within the guide unit when unrestrained, said striping unit being formed with a liquid passage channel and wall port leading to the striping nib end, said slide block also being formed with a wall port therethrough opening from the paint chamber to the slide channel and positioned to coincide with the striping unit wall port when said striping unit is depressed within its supporting slide channel, and a flexible spring guard mounted on an adjustable support frame slidably mounted on the guide unit and movable in alignment with the striping nib, capable of covering the nib end by an inward displacement of the guard support frame toward the supporting guide unit.

4. A paint striping device adapted for making parallel stripe lines on smooth painted surfaces and used with liquid striping paint, comprising an elongated, tubular, paint container casing closed at both ends and having a guide unit fixedly mounted on one end thereof, the opposite casing end being provided with a closable wall opening suitable for entering liquid paint therein, a slide support block having a plurality of parallel slide channels formed therethrough, fixedly mounted within said tubular casing positioned parallel with the casing axis and projected through the casing end wall within the guide frame unit, a paint striping unit with nib end slidably mounted within each of the said channel slides, each striping unit being formed with a paint passage and wall port, and positioned with the striping nib end within the guide unit, spring means mounted on each of the striping units for retaining them in an extended position within their respective slide channels when unrestrained, said slide support block being formed with wall port openings for each channel slide positioned to coincide with their respective striping unit wall ports, when said units are depressed within said slides.

5. A paint striping guard unit adapted for cutting stripe lines at chosen positions and used in combination with a striping device formed with a striping guide unit and striping nib, comprising a guard unit having mounting slides and slidably mounted on a striping guide unit frame, positioned in alignment with said striping nib, said guard unit being provided with retarding spring members for the mounting slides and with an extended spring leaf positioned thereon to engage and cover the striping nib end when said guard unit is displaced on its slides toward the striping nib.

KARL V. EKLOV.
